UNITED STATES PATENT OFFICE.

ISAAC C. LINDLEY, OF ELIZABETHTOWN, INDIANA.

STRAW-STACKER.

SPECIFICATION forming part of Letters Patent No. 274,205, dated March 20, 1883.

Application filed November 4, 1882. (No model.)

To all whom it may concern:

Be it known that I, ISAAC C. LINDLEY, of Elizabethtown, county of Bartholomew, and State of Indiana, have invented certain new and useful Improvements in Straw-Stackers, of which the following is a specification.

The object of my said invention is to produce an improved carrier for conveying thrashed straw from thrashing-machines to the stacks.

10 Said invention consists in certain arrangements and combinations of mechanism whereby the carrier can be conveniently raised and lowered, and can be run in any direction from the rear of the machine that may be necessary to carry the straw to the proper position on the stack, as will hereinafter be more particularly described.

Referring to the accompanying drawings, which are made a part hereof, and on which 20 the same letters of reference indicate the same or corresponding parts, Figure 1 is a perspective view of a thrashing-machine, a straw-stack, and one of my improved straw-carriers running from the one to the other; Fig. 2, a 25 side elevation of the principal portion of the carrier on an enlarged scale; Fig. 3, a rear elevation of the same, as seen from the dotted line $z z$; Fig. 4, a transverse vertical sectional view, looking to the right from the dotted line 30 $y y$, and Fig. 5 a plan of the portion of the way D beyond the broken lines in Fig. 2.

In said drawings, the portions marked A represent the thrashing-machine; B, the supporting frame-work of my improved straw-carrier; C, the pivot-shaft; D, the carrier-way; E, F, G, and H, the various shafts which 35 constitute part of the mechanism of the carrier, and I the traveling carrier.

The machine A may be any thrashing-machine 40 capable of ordinary use, and should be provided with a pulley, a , from which to run a belt to the carrier.

The frame-work B is an upright frame-work supported by sills or feet B', or otherwise, and 45 carries the various shafts and other mechanism essential to my invention. It is composed of the posts $b b$ and the cross-timbers $b' b' b'$.

The pivot-shaft C is mounted upon the cross-timber b' , and passes up through the cross-

timber b^3 , and bears upon its upper end the 50 bolster C', which has bearings $c' c^2 c^3$ for the shaft G, and the supports for the carrier-way. It also has a flange, c , upon which a brake or clamp, as the clamp-screw c^4 , may be applied.

The carrier-way D is similar to the ways which usually form part of ordinary straw and like carriers. It has supporting-brackets d , which rest in the bearings $c' c^3$, and in which they rock. It is also provided with flaring 60 sides d^2 at its lower end, the better to catch the straw from the machine. This carrier-way is composed of sections, as usual, by which it may be extended to any ordinary length; but when it is desired to run it somewhat farther 65 than usual a lighter and more easily attached extension is provided. This last-mentioned extension is formed of removable sides D', which are adapted to be connected to the regular carrier-way by hinge-like attachments d^3 , and cross-rods d' , which are bent at the ends, as shown, or otherwise provided with heads, and are adapted to be passed through openings or slots in the sides D' and turned therein, (see Figs. 2 and 5,) which forms a sufficiently 70 strong and steady construction for this purpose, and, being much lighter than the solid way, is much more easily handled in the position where it is desired that it shall be used. A light removable floor is laid upon the rods 75 d' after they are placed in position, thus making the floor of the way continuous, as well as the other parts. The floor to the extension is not shown in the drawings, however, as it would cover other portions which it is desired 80 to illustrate. (See Fig. 5.) The opening through the bracket d , through which the shaft G passes, is sufficiently large so that said bracket shall not rest upon said shaft, but upon a seat therefor in the bearing c' .

The shaft E is mounted in bearings on the frame-work B, and bears upon one end the pulley e and upon the other the miter gear-wheel e' .

The shaft F is mounted at the lower end in the stop f , and passes up through the cross-bar b^2 and the hollow pivot-shaft C. It bears upon its lower end the miter gear-wheel f' and upon its upper end the miter gear-wheel f'' .

(Model.)
